UNITED STATES PATENT OFFICE.

PAUL PIGNOT, OF YONKERS, NEW YORK, ASSIGNOR TO ALEXANDER SMITH
& SONS CARPET COMPANY, OF SAME PLACE.

DESIGN FOR A CARPET.

SPECIFICATION forming part of Design No. 13,990, dated June 19, 1883.

Application filed May 4, 1883. Term of patent 3½ years.

To all whom it may concern:

Be it known that I, PAUL PIGNOT, of Yonkers, Westchester county, New York, have invented a new and original Design for Carpets, 5 of which the following is a specification.

The accompanying photograph illustrates my new design for carpets.

This invention relates to a new design for carpets, oil-cloths, and analogous fabrics; and 10 it consists of the new ornamentation of parts, hereinafter more fully pointed out.

The carpet is by two narrow bands, *a* and *b*, divided into three main stripes, A B C. The upper stripe, A, which is the narrowest of the 15 three, contains some Gothic arches. The next stripe, B, contains the representation of a landscape with flowers in front trailing along the posts and beams of an arbor, and a fenced road in the background. The main part C

of the carpet contains the representation of 20 a hillside, with an open path, *d*, representations of bridges *e* and *f*, and representations of trees *g* and flowers *h* in profusion.

I claim—

1. The design for carpets, consisting of the 25 stripe B, which is ornamented, substantially as shown:

2. The design for carpets, consisting of the stripe C, having the figures *d e f g h*, substantially as shown.

3. The design for carpets, consisting of the 30 stripes A B C and bands *a b*, stripe C containing figures *d e f g h*, substantially as shown.

PAUL PIGNOT.
